MACHINE FOR WASHING AND CLEANING
DENTURES OR THE LIKE

Anthony P. Ciccone, Los Angeles County, Calif.
(315 E. Mission Drive, San Gabriel, Calif.)

Filed Apr. 10, 1964, Ser. No. 79,441

Term of patent 14 years

(Cl. D49—1)

FIG. 1.

FIG. 2.

FIG. 3.

FIG. 4.

FIG. 5.

FIG. 1 is a side perspective view of a machine for washing and cleaning dentures showing my new design;

FIG. 2 is a side elevation view thereof;

FIG. 3 is a front elevation thereof;

FIG. 4 is a rear elevation view thereof; and

FIG. 5 is an enlarged top plan view thereof.

I claim:

The ornamental design for a machine for washing and cleaning dentures or the like, as shown.
